UNITED STATES PATENT OFFICE.

WILLIAM PARKS, OF FRAZEYSBURG, OHIO, ASSIGNOR OF ONE-HALF TO ABRAHAM LEVI YOUNG, OF FRAZEYSBURG, OHIO.

STRAINER.

1,314,829.

Specification of Letters Patent. Patented Sept. 2, 1919.

Application filed February 18, 1919. Serial No. 277,795.

To all whom it may concern:

Be it known that I, WILLIAM PARKS, a citizen of the United States, residing at Frazeysburg, in the county of Muskingum 5 and State of Ohio, have invented a new and useful Strainer, of which the following is a specification.

My invention relates to milk strainers and its principal object is to provide a strainer 10 wherein the reticulated or straining element is removable; the latter being mounted in a novel manner.

A further object of the invention is to provide a milk strainer which is simple in construction, durable in use, consists of few parts and which may be manufactured and sold at a minimum cost.

The above and other objects and advantages of the invention will become fully apparent from the following disclosure and the inventive features explicitly defined in the appended claim.

The invention consists of constructions, combinations, arrangement of parts, and 25 general assembly which will be hereinafter specifically referred to and illustrated in the accompanying drawing, wherein:

Figure 1 is a fragmental view of a receptacle having my improved strainer applied 30 thereto;

Fig. 2 is a view showing the reverse side of the strainer and showing the manner of forming the beading;

Fig. 3 is a transverse sectional view of 35 the same taken on line 3—3 of Fig. 1; and

Fig. 4 is an enlarged fragmental view showing the manner of mounting the strainer, taken on line 4—4 of Fig. 1.

Referring in detail to the drawing, the 40 numeral 5 designates a wall of a milk pail or other receptacle which is formed with an upper wall 6 having a discharge opening 7 therein. Formed upon opposite sides of the opening and extending transversely of the same are beadings or ribs 8. A bead 9 is 45 also formed in the wall near its outer edge

which extends longitudinally of the wall 6 and joins the ribs 8. The beading 8 and 9 is formed by forming a depression upon the inner face of the wall 6.

Secured to the ribs or beading 8 and 9 is a discharge spout 10 which includes side walls 11 which are soldered or otherwise secured to the beading 8 and an end wall 12 that is soldered to the beading 9. This manner of attaching the discharge spout affords a space between the wall 6 and discharge spout. The inner edges of the side walls of the discharge spout are bent inwardly and provide guide flanges 13 which are also spaced 60 from the wall 6 and receive a reticulated strainer 14. The inner transverse edge of the strainer 14 is disposed between end wall 13 and the wall 6 of the receptacle and abuts the beading 9.

The embodiment of the invention herein disclosed is considered to be the preferred construction but it is to be understood that the invention may be modified and that my limits of modification are only governed by 70 the appended claim.

What is claimed is:—

In a strainer, a wall having a discharge opening therein, parallel longitudinal beads disposed upon opposite sides of the opening, a longitudinal bead disposed at the lower end of the first-mentioned beads and extending at right-angles thereto and joining the same, a discharge spout having inwardly directed inturned flanges at its edges, the 80 flanges being spaced from the wall by the beads and secured thereto, and a reticulated element insertible between the flanges and wall.

In testimony that I claim the foregoing as 85 my own, I have hereto affixed my signature in the presence of two witnesses.

WILLIAM PARKS.
